LYNN DUANE JOHNSON, OF PORTLAND, OREGON.

FUSE AND CIRCUIT TESTER.

1,249,965.

Specification of Letters Patent. Patented Dec. 11, 1917.

Application filed April 7, 1916. Serial No. 89,546.

To all whom it may concern:

Be it known that I, LYNN D. JOHNSON, a citizen of the United States, and a resident of Portland, in the county of Multnomah and State of Oregon, have invented a new and Improved Fuse and Circuit Tester, of which the following is a full, clear, and exact description.

This invention relates to electrical appliances and has particular reference to a simple, safe and reliable device for testing fuse plugs while in circuit with respect to all voltages within any ordinary range.

Among the objects of the invention is to provide a device of this nature that is practically fool-proof, since with this device there is no danger, such as is incident to a device having a common lamp in an open socket, when, by mistake, a low voltage lamp is used upon a high voltage circuit, causing the lamp to blow up and causing a probable injury due to burning or the flying of glass. The device proposed herein is one in which the terminals are always in series with a coil having a known resistance and a lamp is employed for the maximum high voltage, say, for instance, 600, means being provided to test for any desired lower voltage by varying the effect of the resistance coil.

Another object of the invention is to provide a device of this nature which constitutes a handy tool or implement for the electrician's kit, the device being very small and portable and adapted for use by any electrician or engineer in connection with any works where there is any considerable amount of electricity consumed for light or power.

A further use for the device is by janitors or superintendents of apartment houses or similar buildings for locating blown fuses whereby numerous emergency calls might be eliminated if the person in charge, with a slight knowledge of electricity, is enabled to locate the trouble.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like char-

acters of reference designate the same parts 55 in the several views, and in which

Figure 1 is a perspective view of the appliance complete as it would be carried in one's kit;

Fig. 2 is a plan view of the device with 60 the face plate removed; and

Fig. 3 is a diagram indicating the principal electrical parts.

Referring now more particularly to the drawings, I show a casing 10 of rectangular 65 construction into one end 11 of which are projected a pair of fixed, flexible, insulated contact terminals 12 and 13 constituting fixed parts of the apparatus.

The terminal 12 includes a wire 12' which 70 leads into the interior of the casing where it is connected at 14 to the metallic contact against which the end 15 of a pilot lamp 16 projects. The base 17 of the lamp is fitted in a clamp 18 from which an insulated wire 75 19 leads through a partition 20, separating the interior of the casing into two main parts, to a resistance coil 21 of known high resistance.

While the lamp 16 occupies the major 80 portion of one half of the casing, the coil 21 is fitted snugly in the other half of the casing, occupying approximately two-thirds thereof, but having its upper end spaced from the end 11 of the casing. The coil is 85 locked in position by a vertical bridge 22 of insulation lying in the vertical and longitudinal axis of the coil. The bridge is held positively from lateral displacement by being fitted between pairs of blocks or shoulders connected to the end 11 and end of the coil spool respectively, and therefore it 90 serves to hold the coil from endwise movement.

This bridge 22 carries a plurality of 95 spaced contacts 23, 24 and 25. The contact 23 is connected by a wire 26 to the end of the resistance coil remote from the connection 19. The contact 24 has direct connection with the wire 13' of the outside terminal 13, and a spring contact 27 is likewise connected to the contact 24 and has normal connection at its free end with the contact 23.

A push button 28 projects through one 105 side of the casing and engages at its inner end against the spring 27, said spring serving to hold the push button projected out-

wardly. By pushing the button 28 inwardly against the force of the spring, the spring is removed from the contact 23 and brought into engagement with the contact 25 from which a wire 29 leads to some intermediate portion of the coil 21, thereby reducing the resistance of the coil in proportion to the amount thereof thus cut off.

The face plate 30 of the casing is provided with a peep hole 31 just over the lamp 16 and for ordinary practice the face plate 30 is connected to the casing by fixed means such as screws 32 or their equivalent.

A device made in accordance with the above description would be designed for maximum voltages according to the work or field of operation, and the lamp employed will be of a nature to withstand the maximum voltage. With the coil 21 designed, say, for a voltage of 600, and the outside terminals 12 and 13 being properly positioned upon the circuit or fuse to be tested, if the lamp glows brightly through the peep hole, the operator will know that the voltage will be high, approximating that indicated for the resistance coil. If, however, the brightness of the lamp is reduced, the operator will know that the voltage of the circuit is proportionally lower. If the lamp glows very dimly, the operator will push upon the push button 28, switching the current through the tap wire 29 and spring 27, when the brilliancy of the lamp will again be noted. Since the resistance in this latter condition is much reduced, the lamp will glow proportionally brighter and the voltage will be approximated according to the nature of the apparatus and the relative proportion of the resistance coil that the tap wire 29 cuts off of the resistance. Not only is it intended for the pilot lamp to be used to indicate approximately the different voltages that may be tested, but also to tell if there is any current on the circuit and to determine blown fuses.

I claim:

1. A circuit tester, comprising a rigid casing, a partition therein dividing the interior thereof into two compartments, a pilot lamp

fitted in one of the compartments, a coil of 50 high resistance fitted in one end of the other compartment, a wire leading from the lamp through the partition to one end of the coil, a bracing bridge of insulation between the other end of the coil and the end of the casting holding the coil in position, a series of contacts carried by the bridge, one of which includes a spring bearing normally against one of the other contacts, the last mentioned contact being connected to the latter mentioned end of the coil, the remaining contact having a tap wire leading therefrom to an intermediate portion of the coil, thereby reducing its effective length and resistance, a pair of permanent terminals on the 65 outside of the casing connected respectively with the lamp and the spring contact, and manually-operated means extending through the casing to cause the spring contact to move from one of the other contacts to the 70 remaining contact, substantially as set forth.

2. A circuit tester, comprising a casing having a longitudinally extending partition dividing the casing into two compartments, and provided with a peep hole leading to 75 one compartment, a pair of terminals carried by the casing and extending into the compartments thereof, a pilot lamp mounted in the compartment having the peep hole and connected with one terminal, a coil of 80 high resistance in one end of the other compartment of the casing, a wire leading from one end of the coil through the partition and connected with the lamp, a disk like bridge of insulating material arranged vertically in the casing above the coil, three contacts on the bridge, two of which are connected with the coil, one with an end of the coil and the other intermediate the ends thereof, the third being connected with a 85 terminal, a spring connected with the last named contact and normally engaging the contact connected with the end of the coil, and a push button mounted in the casing and engaging said spring to move it into engagement with the contact connected with the coil intermediate of its ends.

LYNN DUANE JOHNSON.
